ELECTRICAL COOKING UNIT

Joseph W. Myers and Stephen J. Roesch, Philadelphia, Pa., assignor to Proctor & Schwartz, Inc., Philadelphia, Pa., a corporation of Pennsylvania

Application January 1, 1942, Serial No. 425,330

9 Claims. (Cl. 219—37)

This invention relates to electrical heating units and more particularly to surface type units such as those used on electric ranges or other appliances. The invention further relates to ceramic type structures of this general character. Since the invention is particularly directed to cooking units it will be described with reference thereto.

It is the principal object of this invention to provide a ceramic unit of the class described which is inexpensive to manufacture, has high efficiency and is capable of quick heating, is durable and capable of withstanding great thermal and mechanical abuse, and has long life.

In the past, there have been generally two types of cooking units employed. The first of these is the metal sheathed unit, wherein the heating element is encased in and is insulated from a sheath of metal. These units have enjoyed considerable popularity because of their comparatively high efficiency and speed of operation. They are, however, expensive to manufacture; they have a tendency to warp under usage; and in most cases their efficiency tends to decrease with usage as the metal reflector plate employed in conjunction with them tarnishes and becomes dull. The second type of unit is that which employs a heating element mounted on the face of an open refractory support. This type of unit is inexpensive to manufacture, but it is characterized by slow and inefficient operation and shock hazard to an operator. Attempts to improve the operating characteristics of this type of unit by reducing the mass of the back structure have resulted in loss of mechanical strength and resistance to heat shock.

One of the reasons for the inefficiency of the ceramic type of unit heretofore employed is that the transfer of heat to a cooking vessel is effected mainly by thermal radiation. Prior workers in the art have therefore suggested that the heating element be fixed to its refractory support by means of a thermally-conductive but electrically-insulating cement. By this means, it was endeavored to increase the speed and efficiency of the unit. In addition to allowing heating of the cooking vessel by thermal conduction, a cement face is adapted to be made flat and is virtually non-warping. However, the use of cement has given rise to serious difficulties.

Where a heating element is embedded in a heat-conducting cement which in turn is contained in or on a supporting refractory, it is obvious that great thermal strains will tend to exist at their junction. This is naturally due to the

inevitable differences in the thermal conductivities and coefficients of expansion between the two different ceramic bodies. This creates a serious problem as to how to prevent the cement from separating from its support and of maintaining the integrity of the structure as a whole in the face of thermal and mechanical shock. Prior workers in the art have therefore made the heat-conducting cement of very considerable thickness and mass so that the unit was predominately monolithic cement, and the reduced rate of heating and expansion was not expected to exceed the ability of the support to follow it; or they have cemented a large coil into a deep channel, well within the body of a ceramic support and practically heated the body of the refractory support and the cement as a whole. Such structures have not been commercially satisfactory because of their deficiency in speed and low operating efficiency.

By the present invention, there is provided a novel cement-surfaced ceramic type cooking unit in which the heating element is disposed very close to the cooking surface and is distributed as uniformly as possible in respect to said surface, thereby to obtain rapid and highly efficient operation, and the unit is so constructed that it will not disintegrate under the destructive forces of severe thermal or mechanical shocks. The unit comprises a strong deep ceramic support which carries a thin highly-concentrated heating zone at its upper face. The heating element is in the form of a helical coil of small helix diameter, disposed in shallow channels at the face of the deep ceramic support and embedded in cement which surfaces the unit. In operation, the deep ceramic support remains at a relatively low temperature while the thin heating face of the unit is heated to a high cooking temperature. The unit is caused to relieve itself of stresses due to unequal expansion and contraction of the cement and the ceramic support, and the integrity of the thin heating face is maintained, by initially developing a "mosaic" of minute irregular cracks therein which are so imperceptible as to be unnoticeable by the naked eye. This divides the cement face into multitudinous irregular small pieces which are securely locked in place and it also provides a certain amount of flexibility in the cooking face which, while remaining substantially flat, is enabled to adjust itself in response to stresses.

With the foregoing in mind, an important object of the invention is to provide a novel cooking unit comprising a thin flexible cooking face

in combination with a deep strong ceramic support, the said unit being capable of withstanding great thermal shock.

Another object of the invention is to provide in a unit of the class described a novel arrangement for an auxiliary heating element to aid in various cooking operations.

A further object of the invention is to provide a novel structure for connecting the heating elements to the lead wires in a cooking unit of the type described.

Other objects and features of the invention will be hereinafter apparent. The invention may be clearly understood by reference to the accompanying drawings, in which:

Fig. 1 is a perspective view of one form of cooking unit constructed according to the invention, with a portion of the unit broken away and with other portions shown in unfinished state for purposes of illustration;

Fig. 2 is a plan or face view of a portion of the cooking face with the mosaic surface greatly exaggerated as to visibility of the minute cracks;

Fig. 3 is a perspective view of a preferred form of the cooking unit;

Fig. 4 is a plan or face view of the ceramic support with the surfacing cement removed for the purpose of illustration, and showing the end portions only of the heating elements;

Fig. 5 is a bottom view of the ceramic support showing the rib structure thereof and the lead wires from the heating elements;

Fig. 6 is an enlarged fragmentary sectional view of the complete unit taken along line 6-6 of Fig. 5;

Fig. 7 is a fragmentary perspective view of the ceramic support; and

Figs. 8 to 10 are sectional views illustrating different portions of the unit where the lead wires are attached to the heating elements.

Referring to Fig. 1, there is shown an annular electrical cooking unit comprising a deep ceramic support 1 carrying a thin highly-concentrated heating zone at its upper face. The supporting structure is a solid circular brick of ceramic material which is provided with a plurality of radial slots 2. These slots serve to provide for relative expansion between the upper part of the support and the remainder thereof, and thus serve to relieve stresses set up in the brick 1 due to temperature differential. This tends to prevent cracking of the brick 1. The peripheral portion of brick 1 is provided with an overhanging portion 3 which serves to engage the top surface of the range and hold the cooking unit in position. Any suitable high temperature ceramic material may be used for the support. For example, the ceramic material known by the trade name Thermolain is suitable.

Formed in the upper portion of brick 1 is a long shallow spiral channel 4. Separating successive convolutions of channel 4 are rib portions 5, extending upward from and integral with brick 1. Positioned in the channel 4 is a heating element 6, in the form of a helical coil of resistance wire. Overlying and embedding the heating element 6 is a thermal-conducting but electrically-insulating cement 7 which fills the channel 4 and with ribs 5 forms a flat cooking face. The cement also fills the radial slots 2. Heating element 6 is provided with a coating, preferably of enamel, which burns off when the element is heated. An expansion space is thus provided around the wire. This prevents the development of stresses in the

cement due to differential expansion of the cement and wire.

Die 8 is shown extending over the cemented surface; this makes for homogeneity of appearance of the complete cooking unit and gives the face a desired color other than the normal color of the cement and ribs.

In order to provide speedy and efficient operation, the heating source is provided close to and covers the major portion of the cooking surface. In a unit of this type, of about six inch diameter, made for operation at about 1200 watts, the heating element 6 may be formed of Number 23 gauge wire, and may be wound in the helix on a mandrel 10 only slightly larger than its own diameter. This provides a heating coil of approximately $\frac{1}{16}$ inch outside diameter. The channels 4 are only slightly wider than the coil and may have a height such that the depth of cement above the 15 coil is about 0.040 inch. The width of the ribs 5 is limited by considerations of molding and of electrical insulation, and may be made about $\frac{1}{16}$ inch. It will be seen that the source of heat 20 in the unit is very close to the cooking surface, providing greatly increased speed and efficiency. This provides a thin highly heated top affixed 25 to a relatively cool deep massive supporting structure. As stated hereinbefore, such localized heating of the structure gives rise to great thermal 30 stresses which tend to disintegrate the cooking face by causing the cement to break up and become dislodged from the face.

It is therefore necessary to provide a cooking face in which this tendency to disintegrate is overcome. To this end, it is provided that the cement shall assume the form of a large number 35 of individual small pieces within the channel 4. These pieces are separated by minute, almost microscopic cracks. These cracks are so small 40 that they are not readily visible, and special methods must be employed to make them easily visible. Fig. 2 shows a portion of the cooking face with the minute cracks greatly exaggerated as to visibility of the same. In order to provide the 45 cement in the form of a mosaic of small pieces, it is preferred to use a cement composed of refractory oxides or silicates of zirconium bonded with phosphoric acid. This cement has an initial plasticity which permits accommodation to the 50 closely spaced channel ribs when it is in the heated condition before setting. This cement sets at a high temperature, and upon cooling the cement tends to contract slightly faster than the support. This gives rise to the desired mosaic of many fine 55 cracks extending down into the face. While many forms of cement are suitable, a specific example may comprise (by weight) 80 parts of zircon granular, 20 parts of zircon milled, 8 parts of phosphoric acid (commercial, 85%, syrupy), and 60 8 parts of water. It will be realized that a cold setting cement with a proper shrinking on setting might be employed to the same end; however, the above-mentioned cement is preferred as it 65 possesses desirable electrical, thermal, and mechanical properties. It will be obvious that the cracks separating the cement pieces, formed in this manner, are very irregular. Further, the separation of the pieces is of an order of magnitude equal to or less than the surface irregularities 70 between the pieces themselves and between the pieces and the ribs. The pieces are thus locked firmly to one another, to the ribs and to the heating element. Since the cement is composed of a large number of small pieces, each piece 75 may react separately to thermal shock. This

prevents the setting up of the large stresses which tend to disintegrate the face. Further, because of the large number of cracks, no one crack tends under thermal shock to become objectionably large. It has been found that a cooking face made in this manner is unusually resistant to thermal shock, and shows no tendency to disintegrate even under extreme conditions, such as, for example, when the heating element is initially heated at four times its normal energization (for "flash" operation as described in Patent No. 2,207,634), or when ice water is poured over the face in red hot condition. This type of face is also mechanically strong and can stand great mechanical abuse without disintegration. By the provision of this strong, flexible, flat face there is obtained a strong, fast, and efficient ceramic cooking unit embodying the advantages set forth hereinbefore. The appearance of the unit is in no way impaired by the mosaic of cracks, as they may be seen only with great difficulty as related hereinbefore.

In Figs. 3 to 7 there is shown a preferred form of the cooking unit, in which the support structure imposes a smaller thermal load on the heating element and therefore a larger percentage of heat is directed upward to the cooking surface, with consequent increase in speed and efficiency of the unit. Referring to Figs. 3 and 6, a heating face is provided, similar in most respects to that shown in the previous embodiment. Ribs 10, channel 11 (of spiral form), heating element 12, and cement 13 are provided. The various dimensions are similar to those indicated for the embodiment shown in Fig. 1. The same type of flexible face is provided as provided in the previous embodiment.

Annular ribs 14 and 15 are provided on the ceramic support, as shown in Figs. 4 and 6, and serve as guides in positioning the cement on face 9, and in grinding the face flat. It has been found that a good cement of the type described is both a better thermal conductor and a better electrical insulator than the material used for making the back structure. Therefore, it is preferred to provide a thin layer of cement overlying both element 12 and ribs 10. This reduces the electrical leakage of the unit thus increasing the safety to an operator, and it provides an improved thermal path to the cooking surface. In addition, the grinding of cement flat may be easily accomplished while this is still in a somewhat plastic condition, before firing. This is more easily accomplished than the simultaneous grinding of ribs and cement, since the ribs have already been hardened at this stage and are bound to possess irregularities of manufacture. Rib 15 has located therein a plurality of notches 16 (see Fig. 4). Rim 17 and rib 14 have corresponding notches 18 and 19 therein. Radial lines 20 (see Fig. 3) are scored in the cement and extend over the face of the unit between the inner and outer notches for a purpose to be described later.

In order to reduce the mass of the supporting brick and thereby increase the speed and efficiency of the cooking unit, there is provided a support structure in which a large part of the area beneath the cooking surface is reduced to a minimum thickness. In a unit with dimensions as set forth above, the floor thickness beneath the coil 12 may be only 0.03 inch. In order to provide adequate strength for the support, the rib structure shown in Figs. 5 and 6 is provided. A deep thick rib 21 extends beneath the cooking face and substantially follows one of the spires of the spiral

channel as illustrated. At the outer periphery of the support, there are provided a plurality of deep thick rib sections 22 (see Figs. 5 and 7) which are separated by notches or spaces 23 whose angular disposition corresponds to the notches 18 and 19 above mentioned. In other words, the notches 23 are located respectively immediately below the notches 18 and 19. At the inner periphery of the support, there is provided a relatively thin and shallow rib 24 which has notches 25 therein located angularly in correspondence to the notches 23 and disposed immediately below the notches 16. Extending between the notches 23 and 25 are radial lines 26 of reduced floor thickness, the purpose of which will be explained presently. These lines underlie the surface score lines 20 previously mentioned. Between successive lines 26 are radial ribs 27 and 28 extending between the rib section 22 and rib 21 and between rib 21 and rib 24 respectively. Thus, it will be seen that the lines of reduced floor thickness and the associated notches divide the support into sectors, each of which has a strong supporting rib structure and all of these sectors are firmly connected together by the continuous rib 21.

A drastic reduction in the mass of the supporting structure such as that contemplated will inevitably cause the structure to crack. If the unit were to crack in only one or two places, as would occur if other provisions were not made, the cracks would become quite large. The opening and closing of these cracks as the unit heats and cools would subject the portions of the element 12 at the crack to repeated reversals of stress, thus causing crystallization of the wire and consequent early burnout of the element. Also, the crack might become so large as to expose parts of the element 12 presenting a hazard to an operator. Further still, such a crack would be very unsightly in appearance. For these reasons, it is provided that the unit shall crack into a large number of segments, and with this end in view, predetermined parts of the unit are weakened so that cracking occurs at these predetermined locations. It is for this reason that the above-described lines and notches are provided. Since the unit is weakened at the radial lines and associated notches, it will crack when it is heated and cooled. However, it will be noted that this results in the cracking of the face of the unit into a large number of segments (twelve in the drawings). Each of these segments is still firmly attached to the rib 21. The small cracks and the expansion chamber about the wire (due to burning of enamel) prevent crystallization and consequent burnout of the element 12. In other words, the wire is not held firmly on either side of a crack and subjected to expansion and contraction forces, which would impose stresses on the wire at one point. Rather the wire is free to move in the expansion space so that the stress at a crack is distributed over an appreciable length of the wire. Moreover the stresses are distributed over the entire face of the unit by virtue of the large number of the cracks.

In order to provide further support for the unit, and to adapt it for mounting in a range, there is provided an encasing cup 29 (Figs. 3 and 6) of suitable material, ceramic or metal being preferred. Around the periphery of cup 29 is a flange 30 having a downwardly bent lip, which adapts the unit to be mounted on a range. The unit is positioned within the cup 29, and is firmly held therein by cement 31, which extends along the side of the cup 29, and over a portion of the

floor thereof. Cement 31 should have good electrical insulating properties so as to minimize electrical leakage from the unit to the cup. The cup is protected from direct radiation from the unit by expanded or exfoliated mica 32, or other suitable heat insulating material. If desired, the material 32 could be omitted and in lieu thereof suitable reflecting means may be provided to reduce downward transfer of heat. For example the cup itself may be reflecting or an additional reflector may be used.

The ends of the heating elements 12 extend downward through holes in the support and have lead wires 33 connected thereto. These lead wires go to terminals 34 on terminal block 35 which is fixedly mounted on cup 29 as shown in Fig. 3. Some of the lead wires 33 originate at a considerable distance from the terminal to which they connect. Notches 36 (see Fig. 5) are provided in the ribs 27 so that the lead wires 33 may pass through the ribs 27 above the surface of the floor of cup 29. The lead wires 33, passing through the notches 36 are secured therein by cement or other suitable means.

In many instances, in cooking operations, it is desirable to have a low heat for slow cooking. For this purpose there is provided an auxiliary heating element 37 (see Fig. 6). This element might be used, for example, in a cooking system such as is disclosed in the copending application of J. W. Myers, Serial No. 380,341 filed February 24, 1941. A channel 38 is provided directly above rib 21, which is deeper than the remaining channel 11. The element 37 is embedded in this channel below the main heating element 12. The element 37 is preferably of high resistance so as to produce a low wattage.

In Figs. 8 to 10 there are disclosed three forms of the terminal structure (on greatly enlarged scale) employed in the heating unit of Figs. 3 to 7, all embodying the same basic principles and differing only in the nature of ceramic support at the various points and the bending of the lead wire. With reference to Fig. 5, Fig. 8 illustrates the lead wire connection at 39; Fig. 9 illustrates the lead wire connection at points 40; and Fig. 10 illustrates the lead wire connection at 41.

Referring specifically to Fig. 8, the end portion of the lead wire 33 is inserted through a substantial number of the end convolutions of the heating element 12, and the lead wire extends for a short distance in the channel in which the heating element is disposed. Both the heating element and the lead wire extend through the opening 42 immediately adjacent one of the ribs 27. The descending convolutions or spires of the heating element are widely spaced in order to obtain a desired thermal gradient along the joint or connection. The end portion of the heating element is brazed to the lead wire at 43, thus effecting good electrical connection. Since the brazing operation burns off the enamel on the end portion of the heating coil, a layer of paint 44 is applied to the entire joint, as illustrated. Like the enamel, this paint burns off when the unit is first used, thus providing expansion space within the embedding cement 13. This space is very important as it prevents fracture of the heating element, particularly at the bend, due to repeated expansion and contraction.

The presence of the relatively high mass lead wire 33 results in cooling of the adjacent spires of the heating element 12. However, no electrical connection is made between the lead wire 33 and the heating coil 12, until the braze 43 is

reached. It will be evident that the paint 44 initially prevents such electrical connection between element 12 and lead wire 33. When the unit is heated, the burning away of the paint leaves a space between the spires of element 12 and the lead 33, and oxide of the metals of the wire forms in this space, which oxide has a sufficiently high dielectric strength to prevent electrical connection between the spires of element 12 and the lead 33 at the highest voltage developed between them. However, a very good connection is made between the spires of element 12 and the lead 33 at the braze 43. It will be appreciated that the braze 43 does not corrode appreciably, as it is maintained at a comparatively low temperature, because of its own relatively high mass, the proximity of the relatively cool ceramic back structure and the reduction of heat which has occurred along the spires of element 12, due to the wide spacing thereof. The paint 44 prevents adherence of the brazed joint 43 to the cement 13 (as well as providing expansion space). This is important, as it allows free, vertical movement of the brazed joint under heating. If the braze 43 did adhere to the cement 13, fracture of the wire might occur due to the stress set up by heating, and the movement of the lead wire 33 upward might exert a sufficient force to break down the insulating oxide layer between the lead 33 and the element 12.

The above described joint or connection is made prior to the insertion of the heating element 12 in its channel. The lead wire is then inserted downward through the opening 42 until the joint or connection is disposed as illustrated.

Such a lead wire connection eliminates burn-out and has even longer life than the heating element itself. By this connection the temperature of the heating coil is gradually reduced to the temperature of the lead wire, and crystallization due to reversals of stresses is prevented.

The lead wire connection in Fig. 9 is similar to that of Fig. 8, but in this instance the connection extends through a relatively long opening 45 in rib 21. In this instance the layer of paint 44 plays an even greater part because the cement 13 runs down the long opening a considerable distance. While Fig. 9 illustrates the connection for one of the main heating elements at one of the points 40 (see Fig. 5), the connections for the auxiliary heating element are similar.

The lead wire connection in Fig. 10 is also similar to that of Fig. 8, but in this instance the connection extends through an opening 46 immediately adjacent to one of the ribs 28, and the connection is bent as illustrated in order that the lead wire may extend in the desired direction.

While the invention has been disclosed with reference to certain specific embodiments, it will be understood that these place no limitation on the invention, which is capable of further embodiments or modifications. Furthermore, the invention is not limited to cooking units but is applicable to any heating element in which similar problems are encountered.

We claim:

1. In an electrical cooking unit, a ceramic support structure carrying a shallow cooking face, a deep supporting rib located beneath said face, a channel formed in said face, a portion of said channel above said rib being deeper than

the remainder of said channel, an electrical heating element disposed in said deeper portion of said channel, another electrical heating element disposed in said channel and overlying said first-named heating element in said deeper portion, and heat-conducting insulating cement embedding said heating elements, thereby to fix said heating elements in position and to secure the same to said support structure.

2. In a surface cooking unit for electric ranges or the like, a refractory support having shallow and narrow circular channels in its upper portion defined by thin up-standing ribs, said channels and said ribs being of such dimensions radially of the unit that there are not less than four channels per inch in a radial direction, a small-diameter helical heating coil disposed within and substantially filling said channels, and a thermally-conducting electrical-insulating cement filling said channels and forming a thin working face, said cement having a coefficient of contraction such that it develops irregular minute cracks which divide the cement face into a plurality of pieces, whereby the cement face, when rapidly heated or cooled, cannot exert a disrupting force on said support and the thin ribs but is securely locked to the support by the closely spaced ribs against displacement from either thermal or mechanical shock.

3. A cooking unit as defined in claim 2, wherein in the working face of the unit is weakened along radial lines to cause said face to divide into a number of predetermined sections.

4. A cooking unit as defined in claim 2, wherein in said support has a thin floor beneath said coil, and supporting ribs extending downward from said floor.

5. A cooking unit as defined in claim 2, wherein in said support has a thin floor beneath said coil, and supporting ribs extending downward from said floor, and wherein the thin floor is weakened along radial lines to cause the entire upper portion of the unit to divide into a number of predetermined sections.

6. A cooking unit as defined in claim 2, wherein in said support has a thin floor of approximately 0.03 inch thickness beneath said coil, and supporting ribs extending downward from said floor, and wherein the working face and the thin floor are weakened along radial lines to cause the entire upper portion of the unit to divide into a number of predetermined sections.

7. A cooking unit as defined in claim 2, wherein in the ribs separating said channels are approximately one-sixteenth inch in width, the heating coil has an outside diameter of approximately one-tenth inch, the channels are only slightly wider than the coil, and the depth of the cement above the coil is approximately 0.040 inch.

8. In a surface cooking unit for electric ranges or the like, a circular refractory support having shallow and narrow circular channels in its upper portion defined by thin up-standing ribs, a small diameter helical heating coil disposed within and substantially filling said channels, a thermally conducting electrically insulating cement filling said channels and forming a thin working face, said supporting structure being weakened along radial lines to cause the working face to divide into a number of predetermined sections to permit release of stress in said unit in a uniformly distributed manner, said heating coil having been initially provided with a coating of organic material, which on volatilization with heat will leave a small space surrounding the wire of the helix, whereby said coil will not be dangerously stressed at the said radial cracks when the working face divides itself into the said sections.

9. In a surface cooking unit for electric ranges or the like, a strong refractory support having a plurality of thin closely-spaced ribs integral with its upper face and defining narrow channels thereon, a helical wire heating element disposed in and substantially filling the channel width, the outer diameter of said heating coil being about one-eighth of an inch, a refractory thermal conducting electric insulating cement filling the channel spaces around and above said heating element and forming a thin surface layer above the coils, whereby a practical minimum of electrical insulation is provided over and between said coils, and the center of heat of said heating element is disposed near the cooking surface of the unit, the cement having such a coefficient of contraction that it will develop minute cracks which divide the surface into a plurality of small areas, whereby the cement face when rapidly heated cannot exert a disrupting force on said support and the thin channel ribs, and the cement filling and upper layer are securely anchored to said refractory support by the walls of said channels.

JOSEPH W. MYERS.
